CLAIM

(62) Division of application No. 29/296,583, filed on Oct. 24, 2007, now Pat. No. Des. 584,776.

The ornamental design for a paintball loader body, as shown and described.

(51) **LOC (9) Cl.** 21-01

DESCRIPTION

(52) **U.S. Cl.** D21/573

FIG. 1 is a front perspective view of a paintball loader body having the design of the present invention;

(58) **Field of Classification Search** D21/567,

FIG. 2 is a top plan view of the paintball loader shown in FIG. 1;

D21/570-575; D22/100, 101, 103, 104,
D22/108, 109; 124/41.1, 45, 48, 49, 51.1,
124/55, 56, 69, 70-74, 79

FIG. 3 is a bottom view of the paintball loader shown in FIG. 1;

See application file for complete search history.

FIG. 4 is a rear elevational view of the paintball loader shown in FIG. 1;

(56) **References Cited**

FIG. 5 is a front elevational view of the paintball loader shown in FIG. 1; and,

U.S. PATENT DOCUMENTS

FIG. 6 is a left side elevational view of the paintball loader body shown in FIG. 1, the right side elevational view being a mirror image thereof.
